PULLING-OVER MACHINE.

1,169,414.

Specification of Letters Patent.

Patented Jan. 25, 1916.

Application filed June 26, 1911. Serial No. 635,448.

To all whom it may concern:

Be it known that I, RONALD F. McFEELY, a citizen of the United States, residing at Beverly, in the county of Essex and State of Massachusetts, have invented certain Improvements in Pulling-Over Machines, of which the following description, in connection with the accompanying drawings, is a specification, like reference characters on the drawings indicating like parts in the several figures.

This invention relates to pulling-over machines and is shown for purposes of illustration as embodied in a machine similar to that shown and described in prior Letters Patent No. 1,029,387, granted on my application June 11, 1912.

Prior to this invention power pulling-over machines have been so organized that every shoe is pulled to the same extent, or with the same force, which is determined by the adjustment of pulling springs, and there is no practical way for the operator of those machines to govern the pull in accordance with the requirements of individual shoes. While each of the three gripper levers of those machines has a handle by which the gripper associated with it can be moved after the machine comes to rest, it is impractical for the operator under working conditions to make use of these handles to modify the power-driven pulling action of the prior machines. An operator is obliged to employ one hand and sometimes both for presenting the shoe in proper relation to the several grippers and for holding it so that the upper will be securely seized when the machine is started and there is not time or opportunity for the operator to change his position and reach up to the gripper levers between the time when the side grippers, which close last, have seized the upper and taken control of the shoe and the time when the pulling movement is completed.

A feature of this invention consists in means by which the operator can control the upper pulling movement which is effected automatically by the grippers of a power-operated machine. In the illustrated embodiment of this feature of the invention the machine is provided with a novel "damping" mechanism comprising a single dashpot connected by an equalizer to a plurality of grippers and operating to retard by equal

resistance the automatic updraw movement 55 of the side grippers and render that movement comparatively slow so that it is extended considerably beyond the short period during which the power is applied to the machine. The illustrated updraw controlling means further comprises a hand lever connected at one end through the equalizer to the side grippers and having its handle end located in position for the workman to engage it with one hand during the pulling 60 65 of the shoe effected by the power mechanism after he starts the machine with the usual foot treadle. By the use of this feature of the invention the operator is given abundant time to perceive how the shoe is responding 70 to the pull exerted by the grippers and he can manipulate the controlling lever either to increase or to diminish the extent of the pull on the upper or, if he desires, to stretch the upper repeatedly so that each 75 shoe can be treated according to its particular requirements. As I am advised it is new by this invention to provide a power driven pulling-over machine with means controlled by the hand of the operator 80 during the pulling operation to determine the extent of the pulling movement.

In accordance with a further feature of the invention means is provided which is constructed and arranged for operation during a yieldingly effected upper stretching operation to lock the machine against continued stretching action on the upper. In the illustrated embodiment of this feature of the invention the locking means can be 90 made to interrupt the pulling action of the grippers at any point in the gripper movement at which the operator decides that the shoe has been pulled enough. The power mechanism completes its normal movement 95 and stores power in the updraw springs after the grippers are stopped. The operator can thereafter release the locking means and allow additional, manually controlled stretching of the upper by the power stored 100 in the springs. The locking means is shown as arranged to be released automatically at the end of the machine's cycle.

In accordance with another feature of this invention there is also provided novel 105 means for controlling the extent and rate of the pulling movement of the toe gripper relatively to the side grippers. It is desir-

able that the toe gripper operate before the side grippers pull because the upper should be drawn forwardly on the last before the action of the side grippers causes it to bind around the last, and because such initial operation of the toe gripper straightens the upper along the sides of the last and positions it longitudinally of the shoe for the side grippers to seize it at the proper points.

10 There are however two disadvantages that have been encountered in the past. The first is experienced particularly in making shoes on high toed lasts where the upper bridges from the instep to the top of the toe high 15 above the ball and is very difficult to draw down to the wood at the ball against the full tension of the toe gripper. The second difficulty is experienced in connection with the use of a foredrawing movement for the 20 side grippers. This movement is intended to tighten the vamp forwardly along the sides of the shoe. If the toe gripper completes its forward pull and the side grippers thereafter are given their foredrawing 25 movement there is a tendency to twist the upper. The object of this portion of the invention is to meet these conditions while preserving the advantage of pulling by the toe gripper first.

30 To this end a feature of the invention consists in dividing the automatically effected movement of the toe gripper and providing adjustable means to limit that portion of the toe gripper movement which occurs before 35 updraw of the side grippers begins, with or without provision for causing the latter portion of the toe gripper movement to be effected in company with a forward movement of the side grippers.

40 It is furthermore a feature of this invention to operate the toe and the side grippers together to draw the entire upper forwardly with or without first drawing the upper forwardly by the toe gripper alone.

45 The foredrawing movement of the side grippers is effected through a spring and in accordance with a feature of this invention an adjustable stop is provided to limit the extent of that movement. In the illustrated 50 embodiment of this feature of the invention the machine is equipped with a hand lever by which manual foredrawing can supplement the automatic foredrawing and the machine comes to rest with the hand lever 55 against a stop after having effected foredraw during the first part of the side gripper operation. The stop is so arranged that it can be rendered inoperative whereupon the said foredraw spring will effect a further foredrawing automatically after the updrawing movement has been completed.

These and other features of the invention including more important details of construction and combinations of parts will be 60 explained more fully in the following de-

scription, reference being had to the accompanying drawings, and will then be pointed out in the claims.

In the drawings, Figure 1 is a side elevation of a pulling-over machine equipped 70 with this invention; Fig. 2 is a perspective view of the new parts and connected mechanism; Fig. 3 is a vertical sectional detail, and Fig. 4 is a perspective view from the rear and one side for showing better than 75 appears in Figs. 1 and 2 the new parts which have been applied to the machine for embodying this invention.

The machine comprises a head furnishing bearings for a driving shaft 2 controlled by 80 a clutch and clutch rod 3 and having the operating cams of the machine including cams connected by springs 4 and rods 5 with the rear ends of updraw levers 6 from the front portions of which the grippers are 85 suspended for seizing and pulling the upper at the toe and at the sides of the ball. The clutch causes the machine to come to rest with the upper under tension as in Fig. 2 to permit the upper to be adjusted by the 90 tip straightening lever 9 or by manipulation of the handled front ends of the side gripper levers 6.

In accordance with this invention an updraw control lever 20 is pivoted on the fulcrum rod 22 and has fast on it a pinion or toothed segment meshing with a toothed arm 24 of a rock-shaft 25. This rock-shaft has an arm 26 extending over the updraw levers and having a broadened head engaging the 95 upper sides of the levers. This arm is free to turn about its longitudinal axis so that its head can adapt itself to different relative positions of the levers 6 caused by the upper pulling up more on one side of the shoe than 100 on the other as sometimes happens. A bridle 28 embraces the head of arm 26 and also the levers 6, so that the updraw levers can be lifted as well as held down by the hand controlled lever 20. This construction and 105 mounting gives to the headed arm 26 and the bridle 28 the function of an equalizer in the connections between the side gripper levers and the lever 20 and between the said levers and the dash-pot 40. The machine frame 110 has a segment ratchet 30 adapted to be engaged by a pawl rod 32 which slides in the lever 20 and normally stands by gravity out of engagement with the ratchet but can be raised to stop the pulling movement by finger manipulation of its lateral extension 115 33. By engaging the pawl rod 32 with the ratchet 30 the action of the updraw springs 4, tending further to stretch the stock or to take up stock as the elasticity of the upper 120 responds to the pull of the grippers, is arrested.

A cylinder 40 is pivotally supported at 42 upon the frame back of the updraw control lever 20 and a piston head 43 therein is con- 13

ected by plunger 44 with the lever 20 to be moved thereby. By means of this dash-pot the updraw of the grippers is retarded and consequently will continue, unless stopped by the pawl rod 32, after the power mechanism has come to rest. At its rear end the cylinder has a puppet valve 45 adjustably held up by a screw 46.

In the use of the machine the shoe is presented as usual to the toe and side grippers 15 with the sole against the sole rest 16 and the toe against the toe gripper and held by the right hand while with one foot the operator depresses the starting treadle and, either before or after stretching the machine, he may seize the updraw control lever and through that lever assume manual control of the updraw power driven movement of the grippers. The rise of the grippers is retarded by the resistance of the air in the cylinder 40 while the power from the driving shaft and cams is stored in the springs 4. The operator watches the effect of the pulling movement upon the upper of the shoe and as soon as the particular upper being stretched has been properly pulled to its last he arrests the pulling movement by setting the pawl 32. If in doubt he applies force to the control lever 20 to retard it to a greater extent than the air resistance does and allows the upper to stretch as slowly as the best results for that particular shoe may require. If desired, he can interrupt the stretching at any point and perform any intervening operation that may be needed as, for example, adjustment of the partially tensioned upper by the tip straightening lever 9 or otherwise. When the lever 20 is then released the upper will be again pulled by the force stored in the springs 4, which can be supplemented by manual force applied to the lever 20 and bridle 28 if desired, in the direction to raise the grippers for repeatedly pulling the upper. This procedure is especially useful in tightening the upper about the last at the back of a high toe. The equalizing connection formed by the swiveled stem of arm 26 of the rock-shaft 25 permits the updraw levers to take relative positions determined by the resistance of the stock on the two sides of the last respectively and furthermore permits the updraw levers to be relatively moved for adjusting the upper transversely about the last while said levers are under control of lever 20 or under control of the dash-pot 40, 43, 44. This procedure is especially useful in tightening the upper about the last at the back of a high toe. The pawl 32 locks the grippers with the upper under any tension selected by the operator for the individual shoe being pulled over, and this makes it possible to treat each shoe according to its individual requirements. This permits the production of machine work having the individualistic

treatment of the shoes heretofore found only in hand work, as well as affording the important advantage over hand work which is obtained by the use of a plurality of grippers pulling the entire shoe at one operation. This invention makes the work easier for the operator because it relieves him of much of the need for reaching up to the updraw levers and straining at them to pull the upper more or to relax it to meet the demands of the shoe in hand. When, in a later portion of the machine's operation, the updraw cams lower the grippers the control lever 20 is swung forwardly and the pawl 32 is automatically disengaged from the ratchet 30. The puppet valve can be adjusted to cause the air pressure to retard the updraw little or much as may be desired or can be fully opened. The machine is shown as having connections from the side gripper levers only to the dash-pot and the control lever 20.

In addition to the adjusting screw 46 a loose stem 48 may be employed which can lift the valve 45 and provide for a manual control of the egress of air from the cylinder without dependence upon adjustment of the puppet valve. As a means for enabling the operator to hasten at times the completion of the pulling movement, as for example when he sees that the condition of the shoe will fully warrant speedier work, I have shown a thumb piece 50 located on the outer side of control lever 20 and having a bell crank 52 at its upper end to which is connected a rod 54 upon the upper face 55 of which, at its rear end, the stem 48 rests. The rod has an inclined face 56 that moves over a rest 58, Fig. 2, depending from the cylinder 40 and causing the rod to lift the valve when the thumb piece 50 is pressed upon. If it is desired to cut out the resistance offered by the dash-pot to the upper stretching movement the thumb piece will be raised to cause the bell crank 52 to actuate the stem 48 to open the valve 45.

The new control for the updraw movement mechanism above described is preferably employed in combination with a foredrawing mechanism which is similar to that shown in United States Letters Patent No. 1,145,381, granted July 6, 1915 on my prior application by which the side grippers are caused automatically, alternatively by a hand lever 91, to pull the upper forwardly at the two sides of the last. This foredrawing mechanism includes a bar 90 attached at its rear end to an upstanding lug on a longitudinally reciprocating slide 86 which derives its movement from a cam roll 87 standing in a track in a cam block on the main driving shaft. To this bar 90 is connected the lever 91 depending from a rock shaft 93 journaled in the machine.

head, and on this rock shaft is a toothed segment which communicates motion through an intermediate gear 94 to a rack 95. This rack has on its front end a guide way 96 inclosing a block which is a part of a pivotal coupling between the rack and the adjacent side gripper. It may be explained that the intermediate gear 94 is a part of a rod that extends across the machine and at its other end has similar toothed engagement with another rack like the rack 95 which is similarly connected to the side gripper which is adjacent to it. The relation of this foredrawing mechanism to the tip straightening mechanism controlled by the lever 9 is fully explained in said Patent 1,145,381 and need not be described here. By these connections it will be seen that the side grippers are actuated forwardly during each power operation of the machine. The cam track for the roll 87 is so formed that this actuation takes place immediately after the side grippers seize the upper and before the uplifting movement of the side grippers has caused the upper to bind upon or frictionally engage the last to an extent to retard the foredrawing of the upper objectionably. It will also be noted that while the foredrawing movement is effected yieldingly, as by a spring 97 in the bar 90, Fig. 2, it is not affected by the retarding action of the dash pot 40. The handled end of lever 91 forms means by which a manual foredrawing can be effected, or a reverse movement of the grippers, and moreover in connection with the hand lever 29 said lever 91 affords provision by which, if the shoe is not satisfactorily pulled, the updrawing tension can be relaxed and the upper foredrawn as the appearance of the shoe may show to be necessary to locate the tip seam or to make the upper fit properly on the last.

The machine is provided, see Fig. 1, with an adjustable stop screw 100 that is located in the path of the lever 91 to limit the foredrawing movement in accordance with requirements of the class of shoes being pulled over, the excess movement from the driving cam being taken up by the spring 97. This stop 100 is carried by a rotatable block having a spring detent 102 which allows the stop to be turned out of the way of lever 91 when further foredrawing movement is desired on a particular shoe.

The toe gripper lever 6 is extended rearwardly at 60 beyond its operating cam slide and has an adjustable screw 61 located over the operating cam slide 62 for the side grippers for engagement with the slide 62 whereby said screw engages the slide and limits the independent updraw of the toe gripper. The extension 60 and screw 61 regulate the amount which

the toe gripper can pull the upper forwardly before the side jaws seize it. In other words, this feature of the invention provides for adjustably regulating the extent of foredrawing effected by the toe gripper relatively to the side grippers. An advantage of this is the avoidance of bowing or curving forwardly the middle of the tip seam which has sometimes resulted from excessive pulling by the toe gripper before the side grippers took hold. This result was liable to occur when the uppers were large for the last. The combinations herein employed provide for regulating the foredrawing of the side grippers and also of the toe gripper. It is also to be noted that the latter portion of the foredrawing by the toe gripper is delayed until the side grippers are prepared to take part in the foredrawing movement whereby provision is made for pulling forwardly the sides and middle of the upper together. It is to be noted that the updrawing movement of the toe gripper is now divided into two steps, the first of which is independent of the side grippers and the second of which is dependent upon movement of the side gripper operating slide 62.

Having explained the nature of this invention and described a preferred embodiment of it, I claim as new and desire to secure by Letters Patent of the United States:

1. A pulling-over machine having, in combination, a plurality of grippers for seizing an upper, power driven mechanism for actuating the grippers to stretch the upper, a spring in which the power is stored and from which it is transmitted to a gripper, a rock-shaft having an arm arranged to govern the movement of a gripper in the direction for stretching the upper, and a hand lever connected with said rock-shaft and operating therethrough to govern the rate at which the gripper shall be moved by the power in pulling the upper.

2. A pulling-over machine having, in combination, a plurality of grippers for seizing an upper, power driven mechanism for actuating the grippers to stretch the upper, a spring in which the power is stored and from which it is transmitted to a gripper, a rock-shaft having an arm arranged to hold the gripper down, a hand lever connected with the rock-shaft, a ratchet, and a pawl on the hand lever normally out of contact with the ratchet and arranged to be set by the hand on said lever to lock the gripper before the movement initiated by the power is completed.

3. A pulling-over machine having, in combination, a plurality of grippers for seizing an upper, power driven mechanism for actuating the grippers to stretch the upper,

yielding means tensioned by the power and reacting to move the grippers, updraw levers through which the grippers are so moved, means moving with the updraw levers in the upper stretching stroke, and a manual control therefor including locking means arranged to be set during the pulling movement to arrest that movement.

4. A pulling-over machine having, in combination, a plurality of grippers for seizing an upper, power driven mechanism for actuating the grippers to stretch the upper, yielding means tensioned by the power and reacting to move the grippers, updraw levers through which the grippers are so moved, a rock-shaft 25 having an arm 26 with a broad end overlying a plurality of the updraw levers, said arm being mounted in the rock-shaft to turn about its own axis to equalize action on updraw levers connected with opposed side grippers, a segment toothed arm 24 on the rock-shaft, and a hand lever 20 engaging the toothed arm and arranged to enable the operator by a pull on the control lever to govern or arrest the power driven movement of the updraw levers in stretching the upper.

5. A pulling-over machine having, in combination, a plurality of pairs of grippers and automatic mechanism for causing the grippers yieldingly to pull simultaneously and to hold under tension the upper at opposite sides of the last, and a single hand lever arranged at the side of the machine for engagement and control by the operator during the operation of the automatic mechanism for governing positively the extent of the movement of a plurality of the grippers.

6. A pulling-over machine having, in combination, a plurality of pairs of grippers and automatic mechanism for causing the grippers yieldingly to pull simultaneously and to hold under tension the upper at opposite sides of the last, a single hand lever arranged at the side of the machine for engagement and control by the operator during the operation of the automatic mechanism for governing positively the extent of the movement of a plurality of the grippers, and a fixed ratchet and a pawl in the lever normally hanging by gravity out of contact with the ratchet and arranged for finger movement into position to lock the control lever and the grippers against further actuation by the automatic mechanism in the direction of the pulling movement.

7. A pulling-over machine having, in combination, a plurality of pairs of grippers and automatic mechanism for causing the grippers yieldingly to pull simultaneously the upper at opposite sides of the last, said grippers being arranged to require the support of the shoe thereto by one hand of the operator, a starting treadle, and a hand lever

arranged for engagement by the free hand 65 of the operator to control the rate and extent of movement of a plurality of the grippers by said automatic mechanism.

8. A pulling-over machine having, in combination, a plurality of grippers for seizing 70 an upper, power driven mechanism for actuating the grippers to stretch the upper, additional means acting automatically to regulate the rate at which the grippers are moved during such actuation, and one means under 75 control of the operator to arrest the movement of a plurality of the grippers before the end of the normal stroke effected by the actuating mechanism.

9. A pulling-over machine having, in com- 80 bination, a plurality of grippers for seizing an upper, power driven mechanism for actuating the grippers to stretch the upper, a dash-pot to regulate the rate of the stretching movement, and a lock under the control 85 of the operator to stop movement at will.

10. A pulling-over machine having, in combination, a plurality of grippers for seizing an upper, power driven mechanism for actuating the grippers to stretch the upper, 90 the controller lever 20 having connections with the grippers, the dash-pot 40, 43, 44 connected with said lever to regulate the rate at which the upper will be stretched if the controller lever remains free, and the 95 pawl 32 carried by the lever to lock the lever and grippers at the will of the operator.

11. A pulling-over machine having, in combination, a plurality of grippers for seizing an upper, power driven mechanism for 100 actuating the grippers to stretch the upper, a single dash-pot to regulate the rate at which the stretching by a plurality of grippers shall normally take place, and a controller lever by which the retarding action 105 of the dash-pot may be supplemented.

12. A pulling-over machine having, in combination, grippers, operating and controlling means therefor including a cam, updraw levers connected with a plurality of 110 said grippers and yieldingly with the cam, additional means normally reducing the rate at which the grippers shall be moved by movement initiated by the cam and transferred through the yielding connection, and 115 means separate from the updraw levers for further controlling manually the rate of movement of the grippers.

13. A pulling-over machine having, in combination, grippers, operating and con- 120 trolling means therefor including a cam, updraw levers connected with a plurality of grippers and yieldingly with the cam, a dash-pot for reducing the rate of movement of the grippers by said operating devices, 125 and a hand lever separate from the updraw lever and affording provision for further reducing or arresting the gripper movement.

14. A pulling-over machine having, in combination, grippers, operating and controlling means therefor including a cam, up-draw levers connected with a plurality of grippers and yieldingly with the cam, means common to a plurality of said grippers for delaying the completion of the updrawing movement while the power is stored in the yielding connection, and a lever having an equalizing connection with said plurality of grippers and adapted for manual manipulation to modify further the updrawing movement of the grippers.

15. A pulling-over machine having, in combination, grippers and operating and controlling means therefor, including an up-draw cam, handled updraw levers connected with the grippers and yieldingly with the cam, a dash-pot, and equalizing connections therefrom to said updraw levers including a hand lever which can be held by the operator during the upper stretching movement to effect further control of that movement.

16. A pulling-over machine having, in combination, grippers, and operating and controlling means therefor including an up-draw cam, handled updraw levers connected with the grippers and yieldingly with the cam, a dash-pot to control the rate of the upper stretching movement, and a lock to arrest the movement at will.

17. A pulling-over machine having, in combination, grippers, and operating and controlling means therefor including an up-draw cam, updraw levers connected with the grippers and yieldingly with the cam, an automatic speed reducing control for the updraw movement, and a manual control therefor separate from the updraw levers and adapted to be used at will.

18. A pulling-over machine having, in combination, grippers, and operating and controlling means therefor including an up-draw cam, updraw levers connected with the grippers and yieldingly with the cam, an automatic speed reducing control for the updraw movement, and a foredrawing mechanism for the side grippers directly connected with the cam shaft to effect foredrawing of the upper while the updrawing is delayed.

19. A pulling-over machine having, in combination, grippers, and operating and controlling means therefor including an up-draw cam, updraw levers connected with the grippers and yieldingly with the cam, an automatic speed reducing control for the updraw movement, and a foredrawing mechanism for the side grippers having an operating handle arranged to permit manual manipulation while the updraw movement is in progress.

20. A pulling-over machine having, in combination, grippers, and operating and controlling means therefor including an up-draw cam, updraw levers connected with the

grippers and yieldingly with the cam, an automatic speed reducing control for the updraw movement, means for arresting the updrawing movement at will, and a fore-draw hand lever connected with the side 70 grippers and adapted for operation while the updrawing movement is interrupted.

21. A pulling-over machine having, in combination, side pulling grippers, an end pulling gripper, automatic means for yieldingly actuating said grippers to pull the upper, a dash-pot control for the speed of the side grippers, an auxiliary manual control for the same, and a foredrawing mechanism connected with the side grippers for 80 manual manipulation at will.

22. A pulling-over machine having, in combination, a plurality of grippers for seizing an upper, power driven mechanism for actuating the grippers to stretch the 85 upper, said mechanism including means by which the movement is yieldingly transmitted to the grippers, and one hand control lever for a plurality of said grippers connected with said mechanism between the 90 grippers and said yielding means and arranged to allow the operator with his hand to govern the rate at which the power is transmitted from the spring to the grippers and to stop or to reverse the pulling move- 95 ment when desired.

23. A pulling-over machine having, in combination, grippers, power updrawing mechanism, foredrawing mechanism, and controlling and operating means by which 100 the workman can stop at will the updrawing movement and manually effect foredrawing.

24. A pulling-over machine having, in combination, grippers, power updrawing mechanism, including a yielding connection 105 and speed reducing means governing the updrawing movement, foredrawing mechanism and devices by which the workman can interrupt at will the updrawing movement and use the foredrawing mechanism and can 110 then cause continuation of the power updraw to take place.

25. A pulling-over machine having, in combination, grippers, automatic operating mechanism therefor including yielding 115 means to impart an upper pulling movement to the grippers, and a dash-pot and connections to govern said pulling movement, said dash-pot having a valve to provide a normally constant regulation of the air escape 120 and means to enable the operator to open the valve to a greater extent at will while the upper pulling operation is in progress.

26. A pulling-over machine having, in combination, grippers, automatic operating 125 mechanism therefor including yielding means to impart an upper pulling movement to the grippers, a dash-pot and connections to govern said pulling movement, a hand lever by which the operator may supplement 130

the action of the dash-pot in governing the upper stretching movement, and means associated with said hand lever to manipulate the dash-pot valve during the upper pulling operation.

27. A pulling-over machine having, in combination, grippers, automatic operating mechanism therefor including yielding means to impart an upper pulling movement to the grippers, a dash-pot and connections to govern said pulling movement, said dash-pot having a valve 45, a rod 54 movable relatively to the valve in a direction to lift the valve and means for actuating said rod, substantially as described.

28. A pulling-over machine having, in combination, toe and side grippers, automatic operating mechanism therefor including yielding means to impart upper seizing and pulling movements to the grippers and being timed to actuate the toe grippers in advance of the side grippers, and means for co-ordinating the latter portion of the toe gripper movement with the side gripper movement.

29. A pulling-over machine having, in combination, toe and side grippers, automatic operating mechanism therefor including yielding means to impart upper seizing and pulling movement to the grippers and being timed to actuate the toe grippers in advance of the side grippers, and an adjustable stop effecting engagement between the toe gripper actuating mechanism and the side gripper actuating mechanism and causing the latter part of the toe gripper movement to be governed by the side gripper movement.

30. A pulling-over machine having, in combination, toe and side grippers, and automatic operating mechanism therefor including yielding means to impart upper seizing and pulling movements to the grippers and being timed to actuate the toe grippers in advance of the side grippers, said mechanism comprising updraw levers and spring connected operating slides for toe and side grippers and an adjustable stop 61 in the toe gripper lever arranged to engage the subsequently actuated slide of the side gripper lever when the toe gripper movement is partially completed.

31. A pulling-over machine having, in combination, toe and side grippers, automatic operating mechanism therefor including yielding means to impart upper seizing and pulling movements to the grippers and being timed to actuate the toe grippers to effect pulling of the upper forwardly in advance of the pulling movement of the side grippers, means to actuate the side grippers to effect foredrawing of the upper, and means to co-ordinate the latter portion of the toe pulling movement forwardly with the side foredrawing movement.

32. A pulling-over machine having, in combination, toe and side grippers, and automatic operating mechanism therefor including yielding means to impart upper seizing and pulling movements to the grippers and being timed to actuate the toe grippers to straighten the upper forwardly and then pause, then to close the side grippers and to actuate the side grippers to pull and foredraw the upper and govern further movement of the toe gripper with the side gripper pulling movement.

33. A pulling-over machine having, in combination, toe and side grippers and mechanism for actuating them to pull an upper, of means for predetermining the extent and rate of pulling movement of the toe gripper relatively to the side grippers.

34. A pulling-over machine having, in combination, a toe gripper, side grippers, and actuating mechanism for lifting the toe gripper and then closing the side grippers and advancing them longitudinally of the shoe while continuing the lifting of the toe gripper.

35. A pulling-over machine having, in combination, a toe gripper, side grippers, and actuating mechanism for causing the toe gripper to seize the upper and pull it longitudinally, to straighten it forwardly and position it in the open side grippers, and thereafter closing the side grippers and causing the side grippers and the toe gripper to pull the upper further forwardly.

36. A pulling-over machine having, in combination, a toe gripper, side grippers, levers by which the several grippers are actuated, yielding means for operating the levers arranged to operate the toe gripper lever first and thereafter to operate the side gripper lever, and a stop on the toe gripper lever arranged to engage a part actuated with the side gripper levers and to limit the independent movement of the toe gripper lever and then allow completion of that movement in company with the side gripper movement.

37. A pulling-over machine having, in combination, side grippers, levers through which they are actuated, yielding means for operating the toe gripper lever, a slide through which the side gripper levers are operated, an extension on the toe gripper lever, and an adjustable stop therein to engage the slide and arranged to permit a limited movement of the toe gripper relative to the side grippers and then to allow further movement of the toe gripper only with the side grippers.

38. A pulling-over machine having, in combination, grippers arranged at opposite sides of the last and adapted for movement to foredraw, stretch and overdraw the upper, automatic means for actuating the grippers, manual means to effect foredraw,

- and adjustable means to be engaged by said manual means for limiting the foredraw without similarly affecting the other movements.
5. 39. A pulling-over machine having, in combination, grippers arranged at opposite sides of the last and adapted for movement to foredraw, stretch and overdraw the upper, automatic means for actuating the grippers, manual means to effect foredraw, and means that is adjustable arranged to engage the manual means to cause the fore-drawing to occur during a greater or less portion of the updrawing movement.
10. 40. A pulling-over machine having, in combination, grippers arranged at opposite sides of the last and adapted for movement to foredraw, stretch and overdraw the upper, automatic means for actuating the grippers, a hand lever that is moved with the foredrawing movement, and a stop that is adjustable in the path of the lever to limit said movement and that can be moved bodily out of said path.
15. 41. A pulling-over machine having, in combination, grippers arranged to seize and pull an upper at opposite sides of a last, power operating mechanism therefor organized to stretch the upper yieldingly at a slow rate such that the operator can watch the effect on the upper, and means adapted for operation during such slow stretching to lock the machine against continued stretching action on the upper.
20. 42. A pulling-over machine having, in combination, grippers arranged to seize an upper at opposite sides of a last, power operating mechanism having yielding connections with the grippers to effect stretching of the upper, and means constructed and arranged for operation during such stretching to lock the machine against continued stretching action on the upper.
25. 43. A pulling-over machine having, in combination, a gripper arranged to seize an upper, power operating mechanism having yielding connection with the gripper to effect stretching of the upper, and means constructed and arranged for operation during such stretching to lock the machine against continued stretching action on the upper and for subsequent manipulation to allow additional stretching of the upper under manual control by power stored in said yielding connection.
30. 44. A pulling-over machine having in combination, a plurality of grippers to which the shoe is upheld in one hand of the operator, power actuated mechanism having a predetermined stroke and yielding connections therefrom to the grippers, a dash pot arranged to regulate the rate at which the power actuation shall take effect on the grippers, and means controlled by the free hand of the operator for simultaneously arresting the movement of the grippers at the will of the operator.
35. 45. A pulling over machine having, in combination, grippers, and operating and controlling means therefor including an up-draw cam, updraw levers connected with the grippers and yieldingly with the cam, an automatic speed reducing control for the updraw movement, and a fore-drawing mechanism for the side grippers arranged to effect fore-drawing of the upper while the updrawing is delayed.
40. 46. A pulling over machine having, in combination, grippers, power driven mechanism for imparting updraw movements to the grippers to stretch the upper, automatic speed reducing means for controlling the updraw, and mechanism to effect fore-drawing movement of the side grippers while the updrawing is delayed.
45. 47. A pulling-over machine having in combination, a plurality of grippers to which the shoe is upheld in one hand of the operator, power actuated mechanism for said grippers, means connected with a plurality of said grippers and arranged in convenient position on the machine for engagement by the free hand of the operator so holding the shoe to control the pulling movement effected by the power, and an equalizing device between said controlling means and the grippers.
50. 48. A pulling-over machine having in combination, a plurality of grippers to which the shoe is unheld in one hand of the operator, power actuated mechanism having a predetermined stroke and yielding connections therefrom to the grippers, a lever arranged in convenient position on the machine for engagement by the free hand of the operator so holding the shoe, and equalizing connections between said lever and a plurality of said grippers to permit manual control of the rate and extent of the gripper movement.
55. 49. In a pulling-over machine having grippers engaging an upper on opposite sides of a last and mechanism including a yielding element operating automatically to cause the said grippers to pull the upper about the last, a dash-pot, a single lever, a connection between that lever and the dash-pot piston, and connections between the said lever and the said mechanism by means of which the operator can, when the yielding element is in operation and simultaneously on both sides of the last, not only stop or retard but also accelerate the pulling action of the grippers that is due to the operation of the automatic mechanism.
60. 50. A pulling-over machine having grippers engaging an upper at the toe and opposite sides of a last and mechanism including a yielding element for the toe gripper operating automatically to cause said gripper to move.

pers to pull the upper about the last, said mechanism being arranged to cause the toe gripper to operate partially in advance of the side grippers, and adjustable means to limit that portion of the toe gripper updraw which occurs before the updraw of the side grippers.

51. A pulling-over machine having grippers engaging an upper at the toe and at opposite sides of a last, power-driven operating mechanism including a yielding element for the toe gripper operating automatically to cause said grippers to pull the upper about the last, said mechanism being arranged to cause the toe gripper to operate partially in advance of the side grippers, and adjustable means to limit that portion of the toe gripper updraw which occurs before the updraw of the side grippers, said machine having means for causing a forward movement of the side grippers and for causing a portion of the updraw movement of the toe gripper to be effected in company with said forward movement of the side grippers.

52. A pulling-over machine having, in combination, grippers, automatic operating mechanism therefor including yielding means to impart an upper pulling movement to the grippers, a dash-pot and connections to govern said pulling movement, and means under the control of the operator during the pulling operation by which to regulate the escape of air from the dash-pot.

53. A pulling-over machine having, in combination, grippers and operating mechanism therefor including springs which from the time the grippers begin to pull until the grippers release the upper have a tendency to act continuously to stretch the upper and to react to take up stock as the elasticity of the upper responds to the pull of the grippers, and means constructed and arranged to be manually adjusted to relieve the grippers from the influence of said springs and prevent continued stretching by the springs.

54. A pulling-over machine having, in combination, grippers for engaging an upper at opposite sides of a last, power-driven operating mechanism, yielding connections through which the grippers are actuated to apply a yielding pull to the upper, and mechanism by which said side grippers may be further actuated unyieldingly in the same direction for applying an unyielding pull to the upper.

55. A pulling-over machine having, in combination, grippers for engaging an upper at opposite sides of a last, power-driven operating mechanism, connections from said mechanism to the grippers whereby they are caused to apply substantially the same pulling force to the upper at each side of the shoe approximately unaffected by unequal insertion of the upper stock into the grip-

pers at the two sides of the last, and unyielding operating mechanism by which a positive pulling force may subsequently be applied to the upper through said grippers.

56. A pulling-over machine having, in combination, grippers for engaging an upper at opposite sides of a last, power-driven operating mechanism, connections from said mechanism to the grippers through which said side grippers are made to updraw yielding, and an actuator and connections to said two side grippers through which the grippers may be made further to updraw the upper positively.

57. A pulling-over machine having, in combination, grippers for engaging an upper at opposite sides of a last, power-driven operating mechanism, connections from said mechanism to the grippers through which said side grippers are made to updraw yielding, and an actuator and connections to said two side grippers through which the grippers may be made further to updraw the upper positively, the yielding pull being predetermined by the adjustment of the machine and the positive pull being controllable by the operator as the operation proceeds.

58. A pulling-over machine having, in combination, last engaging means, toe and side grippers, and operating mechanism therefor organized to produce relative movement of the last and the toe gripper to take the lengthwise slack out of the upper before the side grippers are closed on the upper and then to cause the toe and the side grippers to coöperate in drawing the full width of the upper forwardly on the last.

59. A pulling-over machine having, in combination, last engaging means, toe and side grippers, and operating mechanism therefor organized to produce relative movement of the last and the toe gripper to take the lengthwise slack out of the upper before the side grippers are closed on the upper and then to cause the toe and the side grippers to move the ends and the middle of the tip seam forwardly on the last and to cause the side grippers thereafter to tension the upper transversely of the last.

60. A pulling-over machine having, in combination, last engaging means, toe and side grippers, and operating mechanism therefor organized to cause the toe and side grippers to move together in the direction to coöperate in drawing the upper down the instep of the last and then to cause the side grippers and the last to move relatively in the direction to pull the upper so drawn down into the depression between the instep and the toe of the last.

61. A pulling-over machine having, in combination, a plurality of pairs of grippers and power mechanism for causing the grippers yieldingly to pull simultaneously

and to hold under tension the upper at opposite sides of the last, and a single hand lever arranged at the side of the machine for engagement and control by the operator and having an equalizing connection with grippers located at opposite sides of the last and through which the operator can positively move said side grippers up or move them down according to the requirements of the shoe ascertained by the operator while said grippers hold the upper under tension as described.

62. A pulling-over machine having, in combination, a plurality of pairs of grippers and power mechanism for causing the grippers yieldingly to pull simultaneously and to hold under tension the upper at opposite sides of the last, and a single hand lever arranged at the side of the machine for engagement and control by the operator and having an equalizing connection with opposed side grippers and through which

lever and equalizing connection said side grippers can be moved together either up or down without disturbing the positions of 25 said side grippers relatively to each other.

63. A pulling-over machine having, in combination, a plurality of grippers for seizing an upper, power driven mechanism for actuating the grippers to stretch the upper, 30 a single dash-pot to regulate the rate at which the stretching by a plurality of grippers shall normally take place, and an equalizing connection between two grippers and said dash-pot arranged to permit said grippers to be moved relatively, substantially as described.

In testimony whereof I have signed my name to this specification in the presence of two subscribing witnesses.

RONALD F. McFEELY.

Witnesses:

CHARLES E. GRUSH,
JAMES R. HODDER.

It is hereby certified that in Letters Patent No. 1,169,414, granted January 25, 1916, upon the application of Ronald F. McFeely, of Beverly, Massachusetts, for an improvement in "Pulling-Over Machines," errors appear in the printed specification requiring correction as follows: Page 3, line 18, strike out the word "up-draw"; same page and line, after the word "driven" insert the word *updraw*; same page, line 38, after the period insert the following: *Also, he can pull the control lever 20 forwardly and lower the grippers to relax the tension under which the upper is held. If this is done while the air in the cylinder is still under pressure the reaction of the air will assist the operator in this movement.*; same page, lines 56-59, strike out the words "This procedure is especially useful in tightening the upper about the last at the back of a high toe."; same page, line 120, after the comma insert the word *or*; page 8, line 100, claim 48, for the word "unheld" read *upheld*; and that the said Letters Patent should be read with these corrections therein that the same may conform to the record of the case in the Patent Office.

Signed and sealed this 2d day of May, A. D., 1916.

[SEAL.]

R. F. WHITEHEAD,
Acting Commissioner of Patents.
